(57) **CLAIM**

The ornamental design disclosed for training arm extender.

DESCRIPTION

FIG. 1 is a rear perspective view of a training arm extender showing my new design;

FIG. 2 is a rear plan view thereof;

FIG. 3 is a front plan view thereof;

FIG. 4 is a side elevational view of the left-hand side thereof;

FIG. 5 is a side elevational view of the right-hand side thereof;

FIG. 6 is top plan view thereof;

FIG. 7 is a bottom plan view thereof;

FIG. 8 is a rear perspective view of an alternative embodiment of a training arm extender showing my new design;

FIG. 9 is a rear plan view thereof;

FIG. 10 is a front plan view thereof;

FIG. 11 is a side elevational view of the left-hand side thereof;

FIG. 12 is a side elevational view of the right-hand side thereof;

FIG. 13 is a top plan view thereof; and,

FIG. 14 is a bottom plan view of an alternative embodiment of a training arm extender showing my new design.
